UNITED STATES PATENT OFFICE.

GUY CARLETON DENNEY, OF HINSDALE, ILLINOIS, ASSIGNOR TO AMERICAN ARCH COMPANY, A CORPORATION OF DELAWARE.

ARCH BRICK.

Application filed June 21, 1921. Serial No. 479,237.

To all whom it may concern:

Be it known that I, GUY CARLETON DENNEY, a citizen of the United States, residing at Hinsdale, in the county of Du Page and State of Illinois, have invented certain new and useful Improvements in Arch Bricks, of which the following is a specification.

My invention relates to arch bricks, and especially bricks for fire arches such as are used in locomotive fire boxes, for example.

My object is to adapt one and the same brick to widely varying spans between circulation tubes or other members supporting the arch, so that there shall be no need of keeping on hand bricks of many different lengths. I also aim to make the arches built of such self-adjusting bricks substantially uniform in strength for all spans within their range of self-adjustment, and to obviate or minimize the tendency for cooperating bricks that have fused together in service to break apart in the rough handling which they undergo when a locomotive arch is taken down and replaced again for any reason.

How these and other advantages can be obtained through my invention will appear from my description hereinafter of the best forms of embodiment of the invention at present known to me.

In the drawings, Fig. 1 is a fragmentary diagrammatic view showing a transverse section through a locomotive fire box with an arch therein constructed according to my invention.

Figs. 2, 3, and 4 are enlarged fragmentary views illustrating the adaptability of my type of brick to various spans.

Fig. 5 is a plan view of one of the brick members shown in the arch illustrated in Figs. 1 to 4.

Fig. 6 is an end elevation of such a brick.

Fig. 7 is a side elevation of a modified form of brick, and Figs. 8 and 9 are a corresponding plan and a corresponding end elevation, respectively.

Fig. 10 shows a cross-section of such a brick, taken as indicated by the line 10—10 in Fig. 7.

The fire arch 20 shown in Fig. 1 comprises a plurality of main spans supported by circulation tubes 22 extending lengthwise of the locomotive fire box 23, as well as lateral "half-spans" 24 supported between the outermost tubes 22 and the side sheets 25 of the fire box. Each of the main spans (or individ-

ual main arches) comprises a series of arch units 26 extending lengthwise of the fire box 23, and seen end-on in Fig. 1. Each of the arch units 26 (see Figs. 2, 3, and 4) comprises a pair of refractory fire bricks 30, 30 resting on the tubes 22 as supports and leaning against one another in the middle. For convenience, I shall hereinafter regard the portions of the fire bricks 30 which rest on the supports 22 or against one another as "end", without reference to the proportions of the bricks as determining "length" or "breadth".

The outer end of each brick 30 is hollowed at its lower corner 31, to enable the brick to rest and pivot securely on the support 22 (as shown, in a concave conforming to the cylindrical curvature of this support), and is reduced or bevelled at its upper corner 32. The engaging inner end of the brick 30 has the general conformation best shown in Figs. 5 and 6—i. e., this inner end has a projecting "nose" portion 36 on one side of the longitudinal center line of the brick, and a recess portion 37 on the other side thereof. On one of these portions (as shown, the portion 36), the brick has a convex face 40, and on the other portion (as shown, the portion 37), a hollow face 41. The relative arrangement of the convex and hollow end faces 40 and 41 is such that in the arch unit they correlativey correspond and make multiple line contact; i. e., the convex face 40 of one brick 30 bears against the hollow face 41 of the cooperating brick 30 along more than a single line of contact, and vice versa. This is so in various reciprocally leaning angular relations of the cooperating brick on various spans: on subnormal (short) spans, as in Fig. 2; on normal spans, as in Fig. 3; and

on supernormal (long) spans, as in Fig. 4. As shown, the hollow end face 41 is concavely curved and the end face 40 convexly curved, so that when the fire arch is in service the superficial fusion of the brick will assure their sticking together over a considerable width and area. More than this, the radii and curvatures of the faces 40 and 41 are the same and concentric, so as to give real surface contact (as distinguished from mere line contact) of these correlativey, corresponding complementarily curved bearing surfaces in the various angular relations of the cooperating bricks on various spans. In addition, the centers of curvature of these

105

110

bearing surfaces 40 and 41 are so located that the surface 40 faces downward and the surface 41 upward, so as to assure the most stable mutual support of the reciprocally leaning brick on various spans. Under the varying angular relations of the brick corresponding to the very considerable range of span to which the bricks are intended to adjust and accommodate themselves, the strength of the arch is substantially uniform, and the "surface" character of the contact between the brick is unaffected by the variation in angle.

As shown, the respective upper and lower corners 42 and 43 of the faces 40 and 41 are appropriately bevelled, reduced, or blunted, to minimize breakage and fusion at these exceptionally exposed points. Also, the upper surfaces of the nose portions 36 are inclined downward a little relatively to the general upper surfaces of the bricks, so as to make them flush with one another on normal spans and to minimize their upward protuberance on subnormal spans. As a whole, the inter-engaging ends of the bricks are exact counterparts of one another.

The brick 50 shown in Figs. 7 to 10 differs from that shown in Figs. 2 to 6 in having its main body portion 51 lightened somewhat by recesses 52 in its lower side. Also, the hollowed support engaging edge 53 is slightly recessed at 54 in its middle, to assure a stable two point bearing on the support and obviate rocking and chattering in service.

Each pair of brick members will fuse together probably during the course of the first run made by the locomotive and form, as it were, a single brick which can be removed and replaced as a unit. The construction constitutes what may be termed a three-hinged arch in which the pivot point of the center hinge moves upwardly or downwardly as the outer hinges or pivots move inwardly or outwardly in different spans.

I claim:

1. An arch brick having on one end a convex face and a hollow face adapted to make multiple line contact, respectively, with correlative corresponding hollow and convex faces on one end of another brick in various reciprocally leaning angular relations of such bricks on various spans.

2. An arch brick having on one end concentric concave and convex faces adapted to make contact, respectively, with correlative corresponding concentric convex and concave faces on one end of another brick in various reciprocally leaning angular relations of such bricks on various spans.

3. An arch brick having on one end oppositely curved bearing surfaces, one facing upward and the other downward, adapted to make contact with correlative corresponding complementarily curved down-

ward and upward facing bearing surfaces on one end of another brick in various reciprocally leaning angular relations of such bricks, so as to assure the most stable mutual support of such bricks on various spans.

4. An arch brick having on one end concentric concave and convex faces of the same curvature adapted to make surface contact with correlative corresponding counterpart faces on another brick in various reciprocally leaning angular relations of such bricks.

5. An arch brick having on one end concentric concave and convex faces of the same curvature, the former facing upward and the latter downward, adapted to make surface contact with correlative corresponding faces on another brick in various reciprocally leaning angular relations of such bricks, so as to assure the most stable mutual support of such bricks on various spans.

6. An arch brick having at one end correlative recess and projecting nose portions with end faces concentrically curved to the same radius and adapted to make surface contact with corresponding complementarily curved faces of the counterpart end of another brick in various reciprocally leaning angular relations of the bricks.

7. A brick member for sectional fire box arch constructions in which the members are arranged in pairs with one member engaging the other at their inner ends and with their outer ends supported on the adjacent structure, having on its member engaging end oppositely disposed rounded bearing surfaces of similar curvature which form between the members of a pair a hinge joint of substantially ball and socket character permitting flexure of the members to make them accommodable to substantial variations in the distance between the supporting structures for the outer ends, said rounded surfaces in a pair of members riding on each other with a full bearing during flexure.

8. A brick member for sectional fire box arch constructions in which the members are arranged in pairs with one member engaging the other at their inner ends and with their outer ends supported on the adjacent structure, having on its member engaging end a portion cut away for a distance which is approximately half the width of the member, such formation creating a recess and a projecting nose of substantially equal width, the recess having a rounded bearing surface facing upwardly and the nose having a rounded bearing surface of similar but opposite curvature facing downwardly.

9. An arch construction for fire boxes comprising a pair of brick members adapted to be supported at their outer ends upon the adjacent structure and to lean against each other at their inner ends, said inner ends being substantially counterpart in form and

each having a rounded bearing surface opening upwardly and a similarly curved rounded bearing surface opening downwardly, each of said surfaces extending substantially across the depth of the member.

10. An arch construction for fire boxes comprising a pair of brick members adapted to be supported at their outer ends upon the adjacent structure and to lean against each other at their inner ends, said inner ends being substantially counterpart in form and each having a rounded bearing surface

opening upwardly and a similarly curved rounded bearing surface opening downwardly, said surfaces being so disposed as to constitute, in a pair, a hinge joint permitting flexure of the members to accommodate variations in the span to which they are applied and to provide a surface contact as distinguished from a line contact throughout the range of flexure.

In testimony whereof, I have hereunto signed my name.

GUY CARLETON DENNEY.
